UNITED STATES PATENT OFFICE

NICHOLAS TESTI, OF NEW YORK, N. Y., ASSIGNOR TO GILLETTE SAFETY RAZOR COMPANY, OF BOSTON, MASSACHUSETTS, A CORPORATION OF DELAWARE

SAFETY RAZOR

Application filed November 19, 1931. Serial No. 576,110.

This invention relates to safety razors of the type in which a thin, flexible blade is maintained in position for shaving by co-operating blade-shaping members.

5 An object of the invention is to provide a safety razor of this type having an improved and simplified form of clamping mechanism by which the operations of assembling and disassembling the razor are facilitated and the razor adapted to be packaged in a compact manner or within a relatively small container.

It will be understood that the type of safety razor to which my invention relates is that which includes rigid, blade-shaping members, or members sufficiently rigid in their construction to shape the flexible blade accurately and maintain it reliably in the proper position during the shaving operation. An 15 important feature of my invention consists in providing one of such co-operating blade-shaping members with an internal resilient section which may be utilized as one element of the clamping mechanism. Accordingly I 20 may form resilient tongues within the contour of the guard and in such location that they can be utilized as a portion of the clamping mechanism without in any way interfering with or disturbing those portions of the 25 guard which are critical in determining the shape of the blade.

Where the resilient section is formed in the guard member, the co-operating cap member of the safety razor may be provided with a connecting element such, for example, as a hook which extends into proximity to the resilient sections. As herein shown, I utilize the razor handle as an element of the blade-clamping mechanism and another feature of 35 my invention consists in a handle adapted to be detachably connected with the hook element of the cap and to co-operate with the resilient section or sections of the guard in establishing and maintaining the desired 40 blade-clamping relation of the blade-shaping members and being itself resiliently maintained in upright position by said resilient section.

The desired results are secured as herein 50 shown by providing the guard with connect-

ed semi-circular slits which define spaced, transversely-extending tongues, the latter by reason of their design and material being resilient, and reacting with the handle in a balanced manner to maintain the desired relationship of parts. 55

These and other features of the invention will be best understood and appreciated from the following description of a preferred embodiment thereof, selected for purposes of 60 illustration and shown in the accompanying drawing, in which:

Fig. 1 is a view of the razor in end elevation;

Fig. 2 is a view in longitudinal section; 65

Fig. 3 is a similar view, showing the handle in folded position;

Fig. 4 is a view in transverse section on the line 4-4 of Fig. 2;

Fig. 5 is a view in transverse cross-section 70 on the line 5-5 of Fig. 3;

Fig. 6 is a plan view of the guard member;

Fig. 7 is a cross-sectional view on line 7-7 of Fig. 6;

Fig. 8 is a plan view of one type of blade 75 adapted for use in connection with the razor illustrated;

Fig. 9 is a view in perspective of the cap member;

Fig. 10 is a view similar to Fig. 3, showing the handle as partially disengaged, and 80

Fig. 11 is a plan view of the razor showing the handle in its folded position.

The principal members of the razor comprise a cap and guard with co-operating 85 blade-clamping and shaping surfaces. The cap 10 is of rectangular outline and has an inner concave blade-shaping face with parallel longitudinal edges adapted to engage the blade adjacent to the cutting edges thereof 90 and a pair of spaced blade-locating studs 11 projecting from its concave face. The cap also carries a centrally located hook-shaped element 12 which co-operates with the handle in forcing and holding the blade-clamping members in operative position, as will 95 presently appear.

The guard member is also rectangular in contour having an inner convex face upon which the blade is bent by the action of the 100

cap. The guard is provided with the usual teeth along its opposite edges which extend beyond the cutting edge of the blade, although for purposes of the present invention 5 the configuration of the guard edge is not material. The guard is further provided with a pair of spaced circular apertures 14 to receive the blade-locating studs 11 of the cap. It has also two semicircular slits 15 10 which may be substantially concentric with the apertures 14, and which are connected by a relatively wide central slot 16. The slot is of sufficient width to receive freely the hook 12 of the cap and it, together with the 15 semicircular slits 15 define a pair of wide, tapering, oppositely-disposed tongues extending transversely toward each other. These tongues are sprung slightly downwardly or out from the concave side of the guard, as 20 shown in Fig. 7, and are resilient in character on account of their design and material.

One form of blade adapted for use with the cap and guard members described is shown 25 in Fig. 8. The blade 17 is of thin, flexible material adapted to be bent transversely when clamped between the cap and guard and maintained in use in a position of pronounced transverse curvature. The blade is sharpened at its opposite longitudinal edges and is 30 provided with an elongated central slot 18 of sufficient width freely to receive the hook element 12 of the cap. Near each end of the slot 18 is provided with rectangular enlargements 19 arranged to engage on all four sides 35 with the studs 11 and thus positively locate the blade in respect to the cap 10. The blade is also provided with a central circular opening 20 which is intersected by the slot 18.

The handle 21 of the razor is forked at one 40 end and provided with a cross-pin 22 which is preferably located farther from the square end of the handle than from the sides thereof. The forked end of the handle 21 is designed to receive and fit the hook 12 of the cap. Its 45 end is rectangular in outline and of such dimensions that the cross-pin 22 may be forced into the throat of the hook 12 by slightly deflecting the resilient tongues of the guard member. The hook 12 is reduced in width in 50 its throat portion, as best shown in Fig. 10, and is then somewhat enlarged so that when the cross-pin 22 has once been forced through the throat over the hump at its entrance a limited amount of clearance is afforded. 55 The cross-pin 22 is located in the forked end of the handle 21 so that the extreme corners of the end of the handle are farther from the axis of the pin than the end face of the handle, and in this manner a resilient locking connection is provided in the razor.

A tubular extension member 23 fits 60 telescopically upon the handle 21 and is provided with a threaded opening in its end which cooperates with a threaded stud 24 projecting from the end of the handle 21. The handle

may thus be assembled in the short condition shown in Fig. 2 in which the member 23 is telescopically fitted upon the handle 21, or it may be assembled in elongated position as shown in Fig. 1 in which the tubular member 23 is reversed and acts as the extension. 70

In assembling the razor herein shown, the blade 17 is first placed upon the cap 10 and then the guard 13 is placed upon the blade with the hook 12 projecting through the slot 16 of the guard. With the handle 21 in folded position, as shown in Fig. 10, the cross-pin 22 may be inserted into the hook 12 and in this operation the resilient tongues of the guard are sprung inwardly as already explained. When the handle 21 has reached the position shown in Fig. 3 it may then be swung through ninety degrees into the upright position shown in Fig. 2. In this operation the corners of the handle again displace the resilient tongues of the guard and in this final position they are maintained substantially in the general curved plane of the guard as shown in Fig. 4. Movement of the handle from this position in either direction can be affected only by overcoming the balanced yielding resistance of the resilient tongues, and the result is that the handle is maintained yielding in its normal upright position and at the same time the cap and guard are maintained yielding in their blade-clamping position.

When it is desired to disassemble the razor for cleaning or other purposes the handle is again swung into folded position and then 100 pulled forcibly in the direction to disengage the cross-pin 22 from the hook 12, meanwhile momentarily displacing the resilient tongues. The action of these tongues is sufficiently stiff to maintain the handle reliably in upright position while the razor is in use. The parts of the disassembled razor are each small and consequently the razor can be packed very compactly or placed within a container of relatively small dimensions. 110

Having thus described my invention what I claim as new and desire to secure by Letters Patent of the United States is:—

1. In a safety razor a guard member having a blade-engaging face, said member being formed of resilient material, said member having a central aperture and positioning apertures spaced from said central aperture, all of said apertures being in alignment with each other in the longitudinal central portion of the guard, said guard having slits extending from the central aperture in divergent directions forming a plurality of resilient tongues, two of said tongues extending toward each other and having their free ends normally deflected out of the guard and away from the blade-engaging face of said guard. 115

2. In a safety razor a guard member having a blade-engaging curved surface portion, said member being formed of resilient mate- 130

rial and having a central aperture and positioning apertures spaced therefrom all located in the longitudinal central portion of the member, said member also having a plurality of slits extending divergently from the central aperture, thereby forming a plurality of resilient tongues, two of said tongues being deflected from the guard and away from the blade-engaging surface portion, two of said 10 tongues containing the positioning apertures, the edge of each last-mentioned tongue being equally spaced respectively from its aperture.

3. In a safety razor a guard member according to claim 1, in which the slits and 15 apertures are arranged symmetrically with reference to each other and the guard member, said slits penetrating more than one-half the width of guard and in combination with the central aperture more than one-half 20 of the length of the guard.

4. A safety razor guard formed of resilient material, said guard having an oblong central aperture extending longitudinally of said guard, said guard having slits extending 25 divergently from the ends of the central aperture thereby forming a plurality of resilient tongues, two of said tongues extending transversely of said guard and deflected therefrom at their free ends, two of said tongues extending 30 longitudinally of the guard and provided with positioning apertures.

NICHOLAS TESTI.
